UNITED STATES PATENT OFFICE.

GEORGE DELIUS AND CHARLES P. TATRO, OF SEATTLE, WASHINGTON.

ELECTROLYTIC TERMINAL.

Application filed March 29, 1921, Serial No. 456,586. Renewed September 26, 1923.

To all whom it may concern:

Be it known that we, GEORGE DELIUS and CHARLES P. TATRO, citizens of the United States of America, and residents of the city of Seattle, in the county of King and State of Washington, have invented certain new and useful Improvements in Electrolytic Terminals, of which the following is a specification.

10 Our invention relates to an improvement in electrolytic terminals.

The principal object is to provide a terminal for use particularly in the electrolysis of chlorine and which may be employed in connection with a process for protecting piles such as shown in our pending application Ser. No. 454,165, which will not be attacked by the chlorine liberated.

20 Another object of our invention is to provide a terminal which is easily and conveniently made and which is peculiarly adapted for the purpose of protecting piles by electrolysis.

25 Our invention comprises those novel parts and combinations thereof which are shown in the accompanying drawings, described in the specification, and particularly defined by the claims terminating the same.

In the accompanying drawings we have shown our invention in the form which is now preferred by us.

Figure 1 is an elevation of a pile showing the present invention in use in connection therewith.

Figure 2 is an axial section through a terminal member showing the manner of its connection to the complete terminal.

40 Figure 3 is a transverse section through the terminal member.

Our process of protecting piles, briefly, is to place an anode of an electric circuit in close proximity with the pile as it stands in the water, and to place in the sea-water a cathode. Current being passed through the circuit, chlorine is generated at the anode and it is this chlorine which destroys the teredo and other marine growth which is detrimental to the pile. Two things are necessary in such an anode. The terminal must be sufficiently flexible to enable it to be wrapped about the pile, and the complete terminal, including the terminal members which come in contact with the sea-water and which are the generating points

for the chlorine, must be of such material that they are not attacked by the chlorine liberated.

The complete terminal as shown in Figure 1 consists of an insulated flexible conductor 1 having thereon at intervals terminal members 2, preferably of carbon in the form of graphite. The flexible conductor 1 may be wrapped about the pile, and when current is passed therethrough chlorine is liberated at the terminal members 2 which are secured upon the flexible conductor 1 and in electrical contact therewith. The flexible conductor may be an insulated cable or it might be expanded into an insulated sheath or sheathing which might be wrapped about the pile. Broadly, our invention comprises a flexible insulated conductor and terminal members secured thereon which are exposed to the sea-water and in electrical contact with the insulated conductor.

The conductor 1 shown in Figures 2 and 3 as consisting of metallic wires 10 covered with an insulated sheathing 11. At certain spaced points upon the cable 1, the insulation is cut away as is shown at 12.

At such points we place a terminal member, which is shown herein as formed of two complemental half conductors 20. These members 20 are each provided with a groove 21 in which the insulated conductor 1 fits. The groove should be just large enough to receive the insulation 11 of the conductor 1. By coating the surface of the insulation 11 adjacent the cut away portions 12 with a protective material, such as shellac, and by coating the adjoining surfaces of the two half-conductors 20 similarly, when they are placed together about the conductor 1, the cut away portions 12 are sealed within the terminal members 2. Plugs or seals 22, of non-corroding and preferably of non-conducting material, may be placed about the outer ends of the grooves 21 and about the insulated conductor 1 further to seal the cut away portions from attack by the sea-water.

The half-conductors 20 are provided with transverse holes 23 extending therethrough. These are enlarged at their outer ends to form cups 24. A poured metal, such as babbitt, is poured into the holes 23, one end thereof being closed as by a plug 25 which may be of non-conducting material and not affected by the chlorine. This is,

permitted to run into the cups 24 at the outer ends of the holes 23, forming the double-headed pin 3, and in contracting, the metal will draw the two half-conductors 5 firmly together and will hold them upon the conductor 1. The poured metal comes in intimate contact with the strands 10 of the conductor which have been exposed by cutting away the insulation at 12, and forms 10 the electrical contact between the strands 10 and the conductors 20. A second plug 25 may be fitted into the cup 24 opposite that first plugged.

We have found it desirable preliminarily 15 to surface the strands 10 of the cut away portion with tin, lead, or solder, in order that the poured metal will more surely make electrical contact therewith. The terminal member thus secured in place has all metallic parts sealed against exposure to the sea-water. The conductors 20, are, however, in 20 electrical contact with the strands 10 through which current is supplied thereto. The carbon is not corroded by the chlorine 25 which is liberated, nor is it affected by exposure to the sea-water.

If desired the exterior surface of the terminal members 2 may be coated very 30 lightly with paraffin, by heating them and rubbing paraffin thereover. The only apparent advantage of this is to prevent absorption of moisture by the carbon of which the terminal members are formed. This may be omitted if desired.

35 What we claim as our invention is:

1. An electrolytic terminal comprising a flexible insulated conductor, and terminal members secured at intervals thereon and electrically connected to the conductor.

40 2. An electrolytic terminal comprising a flexible insulated conductor, the insulation being cut away at intervals, and terminal members secured upon and in electrical connection with the conductor at such points, 45 and sealed thereon to prevent contact between the conductor and the electrolyte.

3. An electrolytic terminal for use in the generation of chlorine comprising an insulated conductor, and a terminal member 50 of graphite secured thereon and electrically connected thereto.

4. An electrolytic terminal member for use in the generation of chlorine formed of graphite, the exposed surface thereof being

substantially covered with a light film of 55 paraffin.

5. An electrolytic terminal member comprising two longitudinally-separable complementary conductors adapted to fit about 60 and be secured upon a cable.

6. An electrolytic terminal member comprising, in combination with an insulated cable conductor, two complementary conductors adapted to fit about and be secured upon said cable, the ends of said conductors 65 having depressions surrounding the cable adapted to receive a sealing material.

7. An electrolytic terminal member comprising, in combination with an insulated cable conductor, two complementary conductors adapted to fit about said cable and each 70 having a groove for the reception of the cable, and means for securing together said members and for securing them upon the cable.

8. An electrolytic terminal member comprising, in combination with an insulated cable conductor, a pair of complementary conductors adapted to fit about said cable, and each having a transverse hole there- 80 through, a poured metal pin in said holes to secure the conductors together, and non-conducting plugs in the outer ends of said holes to protect said pin from the electrolyte.

9. An electrolytic terminal member comprising, in combination with an insulated cable conductor having the insulation removed at a given point, a pair of complementary conductors adapted to fit about said 90 cable to span the bared conductor and each having a transverse hole therethrough, and a groove to receive said cable, a poured metal pin in said holes to secure the conductors together and to complete the electrical 95 contact between the terminal conductors and the cable conductor, seals closing the outer ends of said holes to protect the metal from the electrolyte, and seals for sealing the ends of said conductors about the cable.

10. An electrolytic terminal member comprising an insulated conductor, and a plurality of terminal members secured thereon and in electrical connection therewith.

Signed at Seattle, King County, Washington, this 23rd day of March, 1911.

GEORGE DELIUS.
CHARLES P. TATRO.
